UNITED STATES PATENT OFFICE

OTTO H. LIEBICH, OF CHICAGO, ILLINOIS, ASSIGNOR TO THE KOHLER-LIEBICH COMPANY, OF CHICAGO, ILLINOIS, A CORPORATION OF DELAWARE

DESIGN FOR A CHIME LAMP OR SIMILAR ARTICLE

Application filed May 2, 1930. Serial No. 35,474. Term of patent 3½ years.

To all whom it may concern:

Be it known that I, Otto H. LIEBICH, a citizen of the United States, and a resident of the city of Chicago, in the county of Cook and State of Illinois, have invented a new, original, and ornamental Design for a Chime Lamp or Similar Article, of which the following is the specification, reference being had to the accompanying drawings, forming a part hereof.

On the drawings:

I claim:

The ornamental design for a chime lamp or similar article, as shown.

OTTO H. LIEBICH.
